UNITED STATES PATENT OFFICE.

LEROY R. LOUGHBOROUGH, OF ROCHESTER, NEW YORK.

DRAFTING INSTRUMENT.

No. 893,085.

Specification of Letters Patent. Patented July 14, 1908.

Application filed November 11, 1907. Serial No. 401,646.

To all whom it may concern:

Be it known that I, LEROY R. LOUGHBOROUGH, a citizen of the United States, residing at Rochester, in the county of Monroe and 5 State of New York, have invented a new and useful Improvement in Drafting Instruments, of which the following is a specification.

This invention relates to drafting instruments having a ruler or scale provided near 10 one end with a pin or center about which the same may be turned, and opposite some of its graduations with openings which are adapted to receive a pencil point, so that 15 arcs or circles of different diameters may be inscribed by inserting the pencil point in one or another of said openings. An instrument of this kind is shown and described in Letters Patent of the United States No. 844,157, 20 granted to me February 12, 1907.

The object of my present invention is to simplify the construction of the means whereby the center-pin may be adjusted, as required.

25 In the accompanying drawings: Figure 1 is a side elevation of a triangle embodying the invention. Fig. 2 is a fragmentary side elevation of the same, on an enlarged scale, omitting the pin-retaining spring. Fig. 3 is 30 a similar view, partly in section, showing the spring in place.

Similar letters of reference indicate corresponding parts throughout the several views.

One of the bars of the instrument, preferably 35 the base bar A, is in the form of a scale or ruler having the customary graduation-marks along its outer edge.

When the instrument is in the form of a triangle, it may be combined with a protractor B and an angle bar C of forty-five degrees, as shown; but these additional features are optional.

d indicates the openings in the bar A which are adapted to receive a marking or 45 pencil point and which are preferably spaced uniformly and arranged to coincide with numerous graduations of said bar, such as the inch, half-inch, quarter-inch and eighth-inch marks, as shown in the drawings. These 50 openings may be of any suitable shape, but are preferably circular and provided above or below the same with a circular enlargement d', as shown. These enlargements permit the underlying paper or object to be seen 55 a short distance in advance of the pencil point.

At the initial or left hand end of the series of pencil openings d is arranged an aperture E, the upper edge of which is in line with said row of openings and provided with a longitudinal series of notches or seats f adapted to receive an ordinary pin or center g about which the instrument is turned in using it as a compass, as above described. These notches which constitute an auxiliary scale 60 are spaced to form equal divisions or fractions of the spaces between adjacent openings d, so that, if for example, it should be desired to inscribe a circle having a radius equal to an inch and a fraction of an inch 65 less than the smallest graduation represented by adjacent openings d, this can be done by placing the pin g in the corresponding seat f. In the construction shown, the pencil-openings d correspond to graduations representing 70 an eighth of an inch, while the pin-seats f are spaced to represent thirty-seconds of an inch.

H indicates a spring or elastic tongue extending across the front sides of the pin-seats f 80 and serving to retain the center-pin in any seat in which it may be placed. The seats are preferably somewhat shallower than the thickness or diameter of the pin, so that the spring is deflected by the pin upon inserting the latter in a seat, as shown in Fig. 3, thus reliably holding the pin therein. The spring is secured in place by any suitable means. In the preferred construction shown, its left hand end is secured in a slot i extending downwardly 90 from the contracted end of the aperture E and having lateral enlargements or holes i' which communicate with the slot. After inserting the lower end of the spring in this slot, it is reliably confined therein by plugs 95 or rivets j driven into said holes, the rivets expanding and clamping or pinching the spring against the walls of the slot. The enlargements i' are preferably arranged on opposite sides of the slot and out of line with each other, as shown, so that the rivets clamp the spring at different points. This spring forms a simple, neat and inexpensive retaining device for the center-pin.

In the construction shown in the drawings, the first or extreme right hand graduation of the auxiliary scale is marked zero, and those pencil-openings d coinciding with the inch and half-inch graduations of the main scale are numbered 1, 2, 3 etc. By this arrangement, upon inserting a pin in the zero seat f and placing a pencil-point say in the

opening marked 1, the diameter of the inscribed circle will be one inch. If, for example, it is desired to inscribe a circle having a diameter of one inch and a sixteenth, the 5 pencil point is placed in the same opening, but the pin is shifted one notch to the left; while if the circle is to have a diameter of one inch and an eighth, the pin is shifted two notches to the left, and for a circle of an inch 10 and three sixteenths, the pin is placed in the extreme left hand notch.

I claim as my invention:—

1. An instrument of the character described, comprising a bar having a row of 15 openings adapted to receive a marking point and a series of seats for a center pin spaced relatively to said openings, and means for retaining a center-pin in one of said seats, substantially as set forth.
- 20 2. An instrument of the character described, comprising a bar having a row of openings adapted to receive a marking point and a series of seats for a center pin arranged at one end of said row of openings, and a pin-25 retaining spring extending across said seats, substantially as set forth.
3. An instrument of the character described, comprising a bar having a row of openings adapted to receive a marking point 30 and an aperture arranged near one end of said row of openings, one edge of said aperture being in line with said row of openings and having a series of pin-notches, and an

elastic member extending across the front side of said notches, substantially as set forth. 35

4. An instrument of the character described, comprising a bar having a row of openings adapted to receive a marking point and an aperture arranged near one end of 40 said row of openings, and provided in its edge with a series of pin-notches, said aperture having a slot provided with an enlargement, a spring seated with one end in said slot and extending with its free portion across said notches, and a plug arranged in 45 said enlargement and bearing against said spring, substantially as set forth.

5. An instrument of the character described, comprising a bar having a row of 50 openings adapted to receive a marking point and an aperture arranged near one end of said row of openings and provided in its edge with a series of pin-notches, said aperture having a slot provided at opposite sides with enlargements arranged out of line with 55 each other, a spring seated with one end in said slot and extending with its free portion across said notches, and plugs driven into said enlargements and bearing against said spring, substantially as set forth. 60

Witness my hand this 29th day of October, 1907.

LEROY R. LOUGHBOROUGH.
